UNITED STATES PATENT OFFICE

2,376,924

WIRE-FEEDING MEANS FOR FASTENING
INSERTING MACHINES

Harold Lane and William Arthur Barton,
Leicester, England, assignors to United Shoe
Machinery Corporation, Flemington, N. J., a
corporation of New Jersey

Original application July 18, 1942, Serial No.
451,446. Divided and this application August
13, 1943, Serial No. 498,544. In Great Britain
June 7, 1940

3 Claims. (Cl. 1—20)

This invention relates to fastening-inserting machines and is herein illustrated as applied to a machine of the type disclosed in Letters Patent of the United States, No. 2,358,862, granted September 26, 1944, on an application filed in our names, of which this application is a divisional, said machine having means for tensioning a shoe upper over a last and fastening-inserting means movable relatively to the last into position to fasten the upper to a sole. It will be understood, however, that this invention is not limited to machines of that particular type nor, in certain respects, to machines for fastening shoe uppers.

Machines of the type referred to are each provided with means for forming a fastening, for example, a staple from a continuous strand of wire. After the fastening has been formed, it is driven into the work by fastening-inserting means provided in the machine. The staple wire is usually wound up on a reel rotatably mounted on the machine frame and wire feeding mechanism is provided which, prior to the forming of a fastening, serves to feed a length of wire into the fastening-forming means where the length of wire is severed from the supply and formed into a fastening. By reason of the winding of the wire on the reel, it has a tendency when being drawn from the reel and presented to the fastening-forming means to curve in one direction and thus to make accurate measuring of the length of wire difficult.

In order to insure accurate measuring of a length of staple wire fed into the fastening-forming means in spite of the afore-mentioned tendency to curve in one direction, the invention provides means associated with the fastening-forming means and arranged to receive the leading end of the wire and to guide it in a substantially straight path during the wire feeding operation. As illustrated, the fastening-forming means is provided with an outside staple former with which is associated a wire receiving spring-pressed member or plunger. The plunger, after having received the leading end of the wire, is moved as a result of the feed movement imparted to the wire against the pressure of its spring until its movement is terminated by an adjustable stop. Thus the length of wire fed into the fastening-forming means is guided in a rectilinear path and at the same time, the length of wire to be fed in is accurately determined. Fastenings of predetermined length are formed in accordance with the thickness of the work into which a particular fastening is to be inserted.

The above and other features of the invention

will now be more particularly described by reference to the accompanying drawing and will be pointed out in the claims.

In the drawing,

Fig. 1 is a view in left-hand side elevation of a portion of the head of a machine in which the invention is embodied, showing the parts in the positions they assume substantially at the end of the staple driving operation;

Fig. 2 is in part a section on the line II—II in Fig. 1 and in addition, illustrates the wire feeding mechanism; and

Fig. 3 is a section on the line III—III in Fig. 2.

The invention is illustrated as embodied in a machine of the type disclosed in the above-mentioned patent and, accordingly, only such features of the general organization as it is necessary to refer to for an understanding of the invention will be described herein in detail. It will be understood that a machine of this type is provided with a side gage 10 (Fig. 1), a sole rest (not shown) serving to position the shoe, shoe upper tensioning mechanism, and fastening-inserting means such as a staple driving mechanism 13 co-operating with a deflector 14 carried on the forward end of a slide 12, the slide being mounted in the machine head for forward movement toward the operator in a downwardly inclined path, the slide also carrying the staple driving mechanism. 15 The upper tensioning mechanism is arranged progressively to tension unlusted portions of the upper over the last and insole along the edge of the bottom of the shoe, held in the operator's hands. In time relation to each pulling of the upper, a staple is driven by the staple driving mechanism to fasten the tensioned marginal portion of the upper to the insole. As the staple is driven, its legs are engaged by the deflector 14, the deflector acting to curve successive portions 20 of the legs before they enter the work to cause the legs to follow curved paths and to become effectively anchored in the insole. Moreover, in time relation to each upper pulling operation, the slide 12 is moved forwardly to carry the lower end of the staple driving mechanism, usually referred to as a staple guiding nozzle 15 (Fig. 1), and other parts associated therewith, inwardly over the shoe bottom to lay the marginal portion 25 of the upper over the insole, whereupon the staple is driven and thereafter the slide 12 is retracted to its starting position.

In the machine of the above-mentioned patent, the staple wire is fed from a reel of wire and the winding of the wire on the reel causes the wire, 30 when it is drawn from the reel, to have a tendency

to curve in one direction and thus make accurate measuring of a length of wire difficult. To overcome this obstacle, the following mechanism is provided. The present machine has, similar to the machine disclosed in the above-mentioned patent, a wire guiding nozzle 16 (Fig. 2) which, together with a so-called inside staple former 18, is secured to the slide 12 by a screw 19 (Figs. 1 and 2) and, therefore, both members 16 and 18 participate in the forward movement of the slide to form a staple. The wire guiding nozzle 16 serves to present an extent of wire, fed through the nozzle by mechanism disclosed in the above-mentioned patent, to a substantially U-shaped outside former 20 secured to a block 22, together with a wire severing knife 24, the block itself being secured to the machine frame so that the movement of the members 16 and 18 takes place relatively to the outside former 20.

The wire feeding mechanism is illustrated in Fig. 2 and comprises principally two feed rolls 26 and 28 between which the wire coming from the reel (not shown) is gripped. The feed roll 26 is rotated by a pawl and ratchet mechanism through a link 30 operated by a bell crank lever and cam (not shown). The wire, after leaving the feed mechanism, is guided in a flexible tube 32 which is in communication with a wire guiding passage 34 provided in the nozzle 16. As in previous machines of this type, the operation of the wire feeding mechanism is intermittent, the mechanism being operated to feed a length of wire through the nozzle 16 and into the fastening-forming mechanism (outside former 20) immediately prior to the operation of the fastening-forming mechanism. The wire feeding operation of the nozzle 16, to present an extent of wire to the outside former 20, is terminated by an adjustable stop. For the purpose of the present invention, the stop is in the form of a spring-pressed plunger 36 (Fig. 3) slidably mounted in a bore 38 provided in the block 22, the longitudinal axis of the plunger being in alignment with the outlet end of the nozzle 16 when the end of the wire is fed through the nozzle (Fig. 3). One end of the plunger 36 is held by a coil spring 40 located in the bore 38 in the block 22 against the outside former 20 provided with wire guiding slots 42 through which the wire is fed. In the center of the end face of the plunger 36 adjacent to the outside former 20 is formed a small recess into which the end of the wire is fed. The inner end of the spring 40 is mounted on the reduced portion 44 of a screw 46 threaded into the bore

38 of the block 22, the portion 44 acting as an adjustable stop for the plunger 36 when the latter is moved inwardly as a result of the feeding of the wire. The spring 40 is relatively light and, when the wire is being fed through the slots 42 of the outside former 20, the wire end enters the recess in the plunger 36 and, as the wire continues to be fed, the plunger 36 is pushed back until it engages the stop 44, the latter, therefore, determining the length of wire fed in. As the plunger 36 is moved back or inwardly by the wire against the pressure of the light spring 40, the engagement of the wire end with the recess in the plunger 36 causes the wire to be moved in a straight path, with the result that the correct length of wire is measured.

Having thus described our invention, what we claim as new and desire to secure by Letters Patent of the United States is:

1. In a fastening-inserting machine having an inside staple former, an outside former and a nozzle for guiding a length of wire to the outside former, in which the inside former and the nozzle are movable as a unit relatively to the outside former, the provision of means for feeding a length of wire to the outside former and a member arranged to receive the leading end of the wire and to move with it during the wire feeding operation to guide the wire in a substantially rectilinear path.

2. In a fastening-inserting machine having an inside staple former, an outside former and a nozzle for guiding a length of wire to the outside former, in which the inside former and the nozzle are movable as a unit relatively to the outside former, the provision of a member associated with the outside former for receiving the leading end of the wire when the latter is fed and for guiding it in a substantially rectilinear path to its stopping position, and a spring for normally maintaining said member in its wire receiving position.

3. In a fastening-inserting machine having an inside staple former, an outside former and a nozzle for guiding a length of wire to the outside former, in which the inside former and the nozzle are movable as a unit relatively to the outside former, the provision of a spring-pressed member associated with the outside former for receiving the leading end of the wire while the latter is being fed and for guiding it in a substantially rectilinear path, and a stop for limiting the movement of said member.

HAROLD LANE.

WILLIAM ARTHUR BARTON.
